UNITED STATES PATENT OFFICE

115,336

DESIGN FOR A BURNER

Lawrence Jaros, Cleveland, Ohio, assignor to The W. J. Schoenberger Company, Cleveland, Ohio, a corporation of Ohio

Application May 16, 1939, Serial No. 85,028

Term of patent 7 years

To all whom it may concern:

Be it known that I, Lawrence Jaros, a citizen of the United States, residing at Cleveland, in the county of Cuyahoga and State of Ohio, have invented a new, original, and ornamental Design for a Burner, of which the following is a specification, reference being had to the accompanying drawing, forming part thereof, and in which drawing:

I claim:

The ornamental design for a burner, as shown.

LAWRENCE JAROS.
